UNITED STATES PATENT OFFICE.

WILLIAM W. WORD, OF SAN FRANCISCO, CALIFORNIA.

DEVICE FOR MAKING AND SHARPENING ROCK-DRILLS.

No. 826,004.

Specification of Letters Patent.

Patented July 17, 1906.

Application filed December 22, 1905. Serial No. 293,006.

To all whom it may concern:

Be it known that I, WILLIAM W. WORD, a citizen of the United States of America, residing at San Francisco, county of San Francisco, and State of California, have invented certain new and useful Improvements in Devices for Making and Sharpening Rock-Drills; and I hereby declare the following to be a full, clear, and exact description of the same, reference being had to the accompanying drawings, forming a part of this specification.

This invention relates to certain improvements in devices for making and sharpening rock-drills, as hereinafter fully described, and illustrated by drawings that accompany and form a part of this specification.

My improvements consist in movable dies or dollies that act on the edges of rock-drills commonly made of a cruciform section, such dies being held in a horizontal plane when driven forward, but permitted to yield laterally to produce a drawing stroke, moving the material to some extent away from the center toward the points or corners that from the nature of the process are shortened and lack material, and consists especially in a manner of mounting and holding the dollies to secure their lateral movement without the aid of positive devices for that purpose.

The objects of my invention are to dispense with certain details heretofore required in such forging implements, to secure a combined forward and lateral motion of the dies or dollies that act on the edges of the drills, drawing the material from the center toward the points or corners, also to gain celerity in the operation of forging such drills and enable the completion of the edges at one heating while the metal is soft.

To these ends I provide devices as shown in the drawings, Figure I being a plan view on top of the dollies that act on the edges of the drills and their supports with their top plate removed; Fig. II, a front end view of the same; Fig. III, an enlarged view in perspective of the forward or acting ends of the dies or dollies; Fig. IV, a view in perspective or a completed drill-point.

In forging rock-drills all kinds of direct-acting or solid dollies without lateral movement when acting endwise against a rock-drill produce curved anterior edges and a lack of material at the corners required to produce straight transverse edges when the drill is finished. This impediment is over-

come by producing a compound motion of the dies or dollies, as set forth in Letters Patent of the United States No. 731,728, for improvements in rock-drill-forging apparatus, 60 granted to me on the 23d day of June, 1902; but such devices involve operative mechanical details to produce positive lateral movement of the dollies that form the edges of the drills and also demand hand control by an 65 operator.

In my present invention a lateral drawing action of the dollies is produced without supplementary mechanism or effort of an attendant by means of a wedging action between 70 the dollies produced by the transverse edges of the drill not being acted upon and by the form of the dollies in respect thereto.

Referring now to the drawings, 1 is a base or frame in which the dollies 2 and 3 are held. 75 4 and 5 are side bars or gibs against which the dollies 2 and 3 bear and slide. 7 and 8 are elastic or compressible springs (here shown as made of india-rubber) against which the bars 4 and 5 bear, as shown in Fig. I. A 80 cover or cap 9 secures the whole together, leaving the dollies 2 and 3 free to move together longitudinally when struck by a hammer-head 10 and driven forward against a drill end 12.

The drill ends 12 before being acted upon in the present process are rough-forged in the usual manner to a cruciform section by dies that act laterally on the bar, the edges being blunt and irregular, as indicated in Fig. I, 90 and require finishing with straight angular edges, as shown in Fig. IV. The drill 12 when being operated upon by the dollies 2 and 3 is turned at intervals ninety degrees, so the cruciform edges are alternately acted 95 upon by the dollies 2 and 3, the grooves 13 in the latter acting as matrices to produce true edges in straight lines. As, however, the ends of the rough-forged drills are curved, as shown in Fig. I, with a redundancy of metal 100 at the center, direct blows of the dollies produce a want at the corners and the lines of the edges are not filled out as in Fig. IV.

When the dollies are driven forward by the hammer 10 and the grooves 13 come in contact with the horizontal edges of the drill, the angular grooves 14 at the same time come in contact with the vertical edges 15 of the drill, and the dollies being free to spread by reason of the spring-cushions the dollies yield, as indicated by dotted lines in Fig. I, producing a drawing action or blow of the grooves 13.

This latter movement draws the hot metal outward from the center and fulls or completes the corners 17, and when the drill 12 is turned ninety degrees the operation is repeated on the other edge, the work progressing in stages until both edges are complete and in one plane. To permit a free longitudinal action of the dollies 2 and 3 and to provide for wear, the seats of the gibs or side bars 4 5 are recessed beyond the dollies, as shown at 6 in Fig. II. The vertical grooves 14 have the further office of maintaining a true right angle of the drill edges, which might otherwise change their relation when the grooves 13 were acting on the drill-point.

15 I claim—

1. In drill-forging apparatus, a pair of dollies movably mounted in a frame or support, said dollies adapted to be driven forward by a hammer, and at the outer sides of these dollies elastic cushions or springs that permit them to spread and give a drawing stroke laterally, in the manner substantially as described.
2. In drill-forging apparatus, two movable

dollies mounted in a frame or support, said dollies adapted to be driven forward and act on two edges of the drill, yielding lateral guides for the dollies and spring-cushions against which these guides bear, permitting 30 the dollies to expand or move outward from the center, producing a drawing stroke upon the drill edges, substantially as specified.

3. In drill-forging apparatus, a pair of dollies movably mounted in a frame or support 35 adapted to be driven forward by a hammer, their anterior ends grooved to form the edges of the drills to be formed or sharpened and cross-grooved to admit one of the drill edges between the dollies, whereby the latter are 40 spread, producing a drawing stroke away from the center of the drill, substantially as specified.

In testimony whereof I have signed my name to this specification in the presence of 45 two subscribing witnesses.

WILLIAM W. WORD.
